UNITED STATES PATENT OFFICE.

JOHN S. BAKER, OF LOS ANGELES, CALIFORNIA

APPARATUS FOR MARKING CANS AND THE LIKE.

1,267,167.

Specification of Letters Patent. Patented May 21, 1918.

Application filed August 7, 1917. Serial No. 184,935.

To all whom it may concern:

Be it known that I, JOHN S. BAKER, a citizen of the United States, residing at Los Angeles, in the county of Los Angeles and State of California, have invented certain new and useful Improvements in Apparatus for Marking Cans and the like; and I hereby declare that the following is a full, clear, and exact description thereof, reference being had to the accompanying drawings, which form part of this specification.

This invention relates to mechanism for automatically marking packages or cans, and the like, as such cans are carried past the marking apparatus by a suitable conveyer.

The invention provides a novel marking apparatus particularly well adapted for use in connection with machines for packaging goods, and especially designed for use in canneries. The marking apparatus can be located at any desired point beside the can runway or conveyer so that the cans are marked as they are moved therewith. Usually, after the goods are packed in the cans they are stored in warehouses before shipping out to the trade, and it is necessary to put identification marks on cans before packing same in order to identify the different kinds, and different grades of goods.

In general practice cans containing different goods are all stored together, and if each can did not have a proper identification mark on it, it would be impossible to know what the cans contained, therefore usually all cans are marked on the outside with ink; some packers use different letters; and some use just an arbitrary number of lines on the sides of the cans to identify the contents.

I will explain the invention with reference to the accompanying drawings to enable others skilled in the art to understand and use the same; and summarize in the claims the essential features and combinations of parts for which protection is desired.

In said drawings:

Figure 1 is a top plan view of a complete marking mechanism embodying the invention, applied to a portion of a can-way, which latter can be of any suitable construction.

Fig. 2 is an end elevation of such mechanism.

Fig. 3 is a side elevation thereof.

Fig. 4 is a detail view of a liner attachment for the marker.

The cam-way or duct along which the cans or packages are moved may be of any suitable construction; as shown, it is composed of opposite L-irons 1 along which the cans are moved by a conveyer 1^a, which may be of any suitable construction, such as are commonly employed in canneries or in other places where packaged goods or cans are handled; in the example shown the cans stand on end upon the conveyer.

The novel marking devices are attached to the side of the can-way, at any desired point, and as shown comprise a marking wheel 2 rotatably mounted upon a swinging arm 3, pivoted on a bracket 4, which is attached to the side of the can-way, or other suitable support adjacent the side of the can-way; and the marking wheel being supplied with ink from a roll 5 mounted on a lever 5^a pivoted on the lever 3 as hereinafter explained.

The lever 3 is pivoted on the bracket 4 at 3^a and is normally impelled in the direction to move the marking wheel 2 toward the can-way by any suitable means; preferably, as shown, by means of a cord or cable 6 attached at one end 6^a to a short arm 3^b on the lever 3 and passing over a roller 6^a mounted on a stud 4^a attached to the bracket 4 and attached at its lower end to a weight 6^b.

The marking wheel 2 is preferably formed with a series of radially disposed sockets or recesses 2^a on its upper side, in which are fixed marking stamps 7, which may be of any suitable construction, and as shown may be retained in the sockets by means of pins 7^a as indicated in the drawings. These stamps may be readily changed to suit the kind of goods marked. The marking wheel preferably has a peripheral frictional band 2^b of rubber or other suitable material on its periphery adapted to contact with the cans in the can-way as they pass the wheel.

As shown, the marking wheel 2 has a stub shaft 2^c which is rotatably journaled in a bearing 3^c near the outer end of the lever 3. The periphery of the wheel 2 is adapted to project into the can-way through an opening or slot 1^c in the adjacent side thereof, as indicated in the drawings, being yieldingly pressed inward by the action of the weight 6^b upon lever 3. The inward movement of the marking wheel may be limited and regulated by means of a screw 8 tapped through

the outer extremity of the lever 3, and which may be locked when adjusted by means of a nut 8^a. The inner end of the screw 8 is adapted to contact with the side of the can-way 1 and arrest the inward movement of the marking wheel if no can is present in the can-way, or in the space between successive cans in the can-way.

The lever 5^a carrying the ink roll is pivoted at 5^b on the lever 3 and to its outer end is connected one end of a contractile spring 9, the other end of which is attached to a lug on the lever 3 as shown. This spring 9 will hold the roll 5 yieldingly in contact with the stamp wheel 2. The movement of the ink roll 5 toward the stamp wheel is regulatable by a screw 10 tapped through an ear 3^d on lever 3, and screw 10 can be locked in adjusted position by means 20 of a nut 10^a.

The ink roll 5 preferably comprises a hollow ink holder 5^e surrounded by a felt pad 5^f, and the holder 5^e may be provided with numerous small perforations 5^g to allow the ink to work out and be absorbed by the felt pad 5^f, by which it is supplied to the stamps or liners. The ink roll can also be easily lifted off the lever 5 and replaced so that it can be readily cleaned or repaired.

30 The ink roll can be adjusted by bolt 10 to give any desired amount of ink to stamps to make heavy or light impressions, this being important when using different inks, in hot and cold weather.

35 The lever 3 is pivoted on bracket 4 preferably by means of a stub having shaft 3^a stepped at its lower end in an arm 4^c on bracket 4, and having its upper end guided in an eye 4^d on the bracket 4 as indicated in Figs. 2 and 3. The lever 3 may be adjustably mounted on the stub shaft 3^a and can be secured thereon when adjusted by means of said bolts 3^f. This enables the stamp wheel to be adjusted to operate at different 45 points on the cans.

Attached to the side of the can-way opposite the marking wheel is an adjustable can guide plate 11, which may be secured to brackets 1^e attached to the side of the can-way 1, by means of bolts 11^b. Said plate 11 is preferably slotted as at 11^a to permit it to be adjusted toward or from the wheel 2. The receiving end of this guide plate is preferably tapered as at 11^c.

55 The guide plate 11 is adjusted in or out as required to suit different diameters of cans. It is shown in full lines in Figs. 1 and 2, adjusted for large size cans C and in dotted lines adjusted for smaller sized cans C'.

60 Of course, cans of a uniform size are supposed to be passed through the machine at any one time. As these cans pass the marking wheel, which carries the stamps, they contact with the rubber band 2' and revolve 65 the wheel by frictional contact therewith,

the wheel moving out and in as the can passes, and the wheel as it turns brings a stamp into contact with the side of the can, which imprints the can as it passes; and as the can passes the wheel is held yieldingly in contact therewith by the weight 6^b. As the wheel revolves the stamps pass and contact with the roller 5. Screw G is adjusted to permit the marking wheel to project into can-way a sufficient distance to insure the proper length of contact between the can and marking wheel according to the size of the cans, in order to bring only one stamp into contact with each can, as the larger the diameter of the can the more contact surface it has and therefore the wheel will have to be adjusted farther from the can-way for large cans, and nearer for small cans.

The guide 11 is adjusted so that there is just enough room between the guide and can-way side for the cans to pass, the guide preventing the can from being pushed away by the marking wheel. When the can comes in contact with the frictional band on the marking wheel the wheel is turned in the direction of the arrow, Fig. 1, and as the can travels on the marking wheel rolls around the can and marks same and moves back into place as the can passes. The length of contact of the can and wheel is regulated by the screw 8, the marking wheel being permitted to enter the can-way as far as is necessary to insure that the contact of the can with the wheel will only turn it sufficiently to mark one stamp on the can.

In this machine the marking wheel is operated by frictional contact with the cans, which makes it practical on any sized can; the marking wheel swings to and from the can in order to obtain full contact and the proper length of contact of the stamp therewith, and no timing device is required for the marking wheel, as each can turns the marking wheel the necessary circumferential distance to make one stamp on the can.

Some packers instead of using stamps or printing the names, numerals or letters on the cans, simply indicate the different kinds of goods by marking lines on the side of the can. In such cases the marking wheel 2 may be removed and the liner wheel shown in Fig. 4 substituted therefor.

The liner wheel shown in Fig. 4 comprises a disk 2^a having a shank 2^b adapted to fit into the socket 3^c in lever 3, when wheel 2 is removed. This disk 2^a has a frictional marker band 2^d on its periphery which is adapted to contact with the can, indicated at C^e, as the latter passes the marking wheel, and mark a line or strip, indicated at c, on the can; the marker band 2^d being supplied with ink from the roller. The disk 2^a has a central stud or post 2^f and a side post or finger 2^g; and a series of interchangeable marking disks 2^a are provided, each having

a peripheral marking surface similar to the marking band; one or more of these marking disks 2^a can be placed on the disk 2^a, as indicated in Fig. 4, so as to apply any desired number of stripes C to the cans as they pass.

The marking disks 2^a can be readily placed on or taken off of the disk 2^a, and in the example shown any number of lines from 1 to 10 6 can be made on the can C^a by the use of this liner wheel. The canner, when he so desires, can replace the marking wheel 2 with the liner wheel. In my marker the can operates same by contact as it passes. The 15 stamp wheel does not revolve until can contacts same, which prevents an over supply of ink and the gumming of stamps from same, and also insures a perfect mark on the can, as the weight causes a yielding pressure 20 of the marking wheel or liner against the can which makes the stamp or liner sure to revolve if the can moves. If the can stops the wheel stops, and there is no blurring.

In canneries the cans do not pass along the 25 canning lines in regularly shaped order or time, but this does not affect the operation of my liner which only operates when a can moves therepast.

I claim:

30 1. In combination a canway, means for moving cans therethrough, a lever pivoted beside the canway, a marking wheel provided with changeable marking devices mounted upon said lever, means for causing 35 said lever to yieldingly move the marking wheel toward the canway, means for limiting the inward movement of the marking wheel; a second lever pivoted on the first lever, a rotatable inking roll mounted on one end of 40 said second lever, means for yieldingly pressing the inking roll against the marking wheel, and adjustable means opposite the marking wheel to cause the cans to properly contact with said marking wheel.

45 2. In a marking apparatus, the combination of a canway, means for moving cans therethrough, a bracket attached to the canway, a shaft pivoted in said bracket, a lever adjustably mounted on said shaft, a marker 50 mounted on the free end of said lever, means for swinging said lever to hold the marker yieldingly in the canway, and means for inking the marker, means for limiting the inward movement of the marker, and means 55 opposite the marker to cause the cans to properly contact therewith.

3. In a marking apparatus, the combination of a canway, means for moving cans therethrough; a bracket attached to the canway, a shaft pivoted in said bracket; a lever 60 adjustably mounted on said shaft, a marking wheel mounted on the free end of said lever, means for swinging said lever to hold the marking wheel yieldingly in the canway, 65 and means for inking the marking wheel,

means for limiting the inward movement of the marking wheel, and an adjustable guide plate opposite the marking wheel to cause the cans to properly contact therewith.

4. In combination a canway, means for 70 moving cans along said way, a lever pivoted on said canway, a marking wheel idly mounted on the free end of said lever and adapted to project into the canway, means for swinging the lever so as to project the wheel into 75 the way in position to be frictionally engaged with and turned by passing cans, means for arresting the inward movement of said lever to insure that each can shall receive only one mark while passing the 80 marker, and means for inking the wheel.

5. In combination a canway, means for 85 moving cans along said way, a marker, means for moving the marker yieldingly into the canway and means for regulating the inward movement of the marker to limit the required length of peripheral contact thereof with different sizes of cans so as to make only one mark on each can passing the 90 marker.

6. In combination a canway, means for 95 moving cans along the way, a marker having a plurality of stamps, and means for regulating the inward movement of the marker into the canway to insure a proper length 100 of peripheral contact between the marker and cans to bring one stamp on the marker into contact with each passing can.

7. In combination a canway, means for 105 moving cans along said way, marking mechanism adjacent the way, comprising a yielding marking wheel, adjustable means for limiting the movement of the marker into the canway to insure the proper length of 110 peripheral contact between the marking wheel and cans; and adjustable inking means yielding with said marking wheel to prevent over inking.

8. In combination, a canway, means for 115 moving cans along the way, marking mechanism adjacent the way comprising a swinging lever, a rotatable marker wheel thereon and adjustable means for limiting the movement of the marker wheel into the canway so that there will be only sufficient peripheral 120 contact between the marker and cans to insure that only one mark shall be applied to each passing can.

9. In combination a canway, means for 125 moving cans along the way, a marker having a plurality of stamps, and means for regulating the inward movement of the marker into the canway to insure such a length of peripheral yielding contact between the marker and cans as will bring one stamp on 130 the marker into contact with each passing can; with adjustable means opposite the marker to position the cans.

10. In combination a canway, means for 135 moving cans along the way; a rotatable

marker carrying stamps and adapted to be rotated by peripheral frictional contact with the cans, means for yieldingly supporting the marker, and means for adjusting the 5 marker to produce such a length of contact between the peripheries of the marker and cans as will insure that only one stamp shall be applied to each passing can.

11. In combination a canway, a smooth 10 conveyer for moving round cans on end along said way, an adjustable marker adjacent said way adapted to engage the round

cans, means for yieldably supporting the marker movable to and from the canway, and means for limiting the movement of said 15 support so as to project the marker into the canway to permit only such length of peripheral contact between the marker and cans as will insure that only one mark shall be applied to each passing can. 20

In testimony that I claim the foregoing as my own, I affix my signature.

JOHN S. BAKER.
